UNITED STATES PATENT OFFICE

MARTIN KENNEDY, OF FREEHOLD, NEW JERSEY, ASSIGNOR TO A. & M. KARAGHEUSIAN, INC., OF NEW YORK, N. Y., A CORPORATION OF DELAWARE

DISPLAY STAND

Application filed September 10, 1930. Serial No. 481,063.

This invention relates to apparatus for displaying rugs, carpets, or the like. The apparatus is particularly adapted for use in displaying rugs, wherein a plurality of different rugs are joined end to end and supported by a series of rollers journaled in a suitable display frame, over which the string of rugs is draped. It is desirable at times to vary the angle at which light is reflected onto the rugs, in order to display the color and design of the rugs to the best advantage.

The object of this invention is to provide an apparatus for displaying rugs, carpets and the like, wherein a means is provided for varying the angle at which the light rays impinge upon the surface of the string of rugs on display.

In the accompanying drawings:

Figure 1 is a front elevation of a display frame made in accordance with the principles of my invention;

Fig. 2 is an end view of Fig. 1, showing the means adapted to vary the angle of the rug relative to the angle of the light rays impinging on the rug; and

Fig. 3 is a modification, showing an alternate means for varying the angle of the rug, relative to the angle of the light rays impinging upon the rug.

Referring to the drawings, the apparatus comprises suitable spaced end frames 1, 1, each of which comprises feet 2, 2, which are adapted to support tubular frame members 3, the upper extremities of which are fitted to a suitable fitting 4. A bearing 5 is provided in the upper portion of the fitting 4, which is adapted to receive and rotatably support one end of a shaft 6. The lower portions of the tubular frame members 3 are connected by tubular members 7, thereby forming A-frames in conjunction with the tubular members 3.

The A-frames 1, 1 forming the opposite ends of the apparatus are held in spaced relation to each other by means of a longitudinally extending shelf or frame member 14. The display stand is braced against longitudinal distortion by diagonally extending rods 27,

27.

Support arms 8, 8 extend outwardly from and are adjustably mounted on the tubular frame members 3, 3, said support arms 8, 8 each having a longitudinally extending slot 9 adapted to adjustably support one end 55 of a shaft 10 having a roller 11 rotatably mounted thereon, between the end frames 1, 1.

A roller 12, having a plurality of spikes 13 circumferentially about its surface is rigidly mounted on the shaft 6, which is rotatably mounted in the bearings 5, 5 of the end frames 1, 1. On the shelf 14, in the present instance, is mounted an electric driving motor 15, connected through a reduction gear 16 to the sprocket wheel 17, which, in turn, is connected by a sprocket chain 19 to a sprocket wheel 18, rigidly mounted on the shaft 6, the sprocket wheel 18 having a greater diameter than sprocket wheel 17, thereby affording a relatively slower rotation of the shaft 6 with 70 respect to the rotation of the shaft of the reduction gear 16.

Extending longitudinally of and on each side of the display frame is a hollow rock shaft 20, which is rotatably mounted on a rod 75 29 secured at its opposite ends to brackets 21, 21 secured to the cross-members 7, 7 of the A-frames 1, 1 respectively.

Secured to each of the rock shafts 20, adjacent one of the end frames 1, is an arm 22 to the outer end of which is connected one end 80 of a link 23. The opposite end of the link 23 is provided with a head 24 having an elongated slot 25 formed therein. Extending through the slots 25 of both of the heads 24, 24, at approximately the center of the slot, is a pin 26 which extends laterally from an operating arm 27 of a control or reversing switch 28 by which the flow of electric energy 85 to the driving motor 15 is controlled.

Secured to the shafts 20, 20 at spaced intervals therealong are arms 30, 30, to the outer ends of which is rigidly secured a longitudinally extending bar 31, to which is removably secured a second bar 32, adapted to clamp the end of the string of rugs therebetween in order that the string of rugs may be operatively connected to the actuating switch.

Normally the grips 31—32 rest on stops 39 which support the grip bars—31—32 and 100

maintain the links or push rods 23, 23 in the relative positions, with respect to the switch pin 26, as illustrated in Fig. 2.

The switch 28 is adapted to be manually operated by a lever 33 pivotally connected at 34 to a cross-bar 35 on the end frame 1, at one end of the display apparatus. The lever 33 has an elongated slot 36, through which the pin 26 of the switch arm 27 projects.

In the operation of the display apparatus, a strip consisting of a plurality of rugs α , joined end to end, is placed over the rollers 11 and 12 in the manner shown in Fig. 2. The extremities of the said strip α are rigidly held by the grips 31—32 carried by the shaft 20. The switch arm 27 is then thrown, by actuation of the control lever 33, thereby starting the motor 15 and subsequently affording a rotary motion to the roller 12, in one direction, the spikes 13 of the roller 12 engaging the string of rugs α and carry it over the display stand, whereby the pile α^1 on one side of the stand is progressively reduced and the pile α^2 on the opposite side of the stand is accordingly increased. On each of the opposite sides of the said display stand, the rug passes at a predetermined angle over the rollers 11 and 12. When the end of the strip α is reached on one side of the stand, one of the piles α^1 or α^2 , as the case may be, has been entirely removed and the roller 12 pulling on the rug, gives an upward movement to the grips 31—32 to which the end of the rug is attached. The upward movement of the grips rocks the shaft 20 and affords longitudinal movement of the push rod 23, thereby moving the head 24 of the rod until the end of the slot 25 therein engages the switch pin 26, continued movement causing the switch arm 27 to be rocked, throwing the switch and reversing the flow of current to the motor 15. Reversal of the motor 15 affords a relative reversing of the whole strip α of the plurality of rugs and the operation may go on in this manner as long as desired.

The angle at which the light impinges upon the face of the rug strip, intermediate the rollers 11 and 12, may be varied by adjusting the supporting arms 8 to a different position along the tubular side frames 3, or the said angle may also be varied by adjusting the shaft 10 in the slots 9 of the arms 8.

A modification of the means for varying the angle at which light is impinged upon the rug strip is shown in Fig. 3. A substantially semi-circular support 8a, having an arcuate slot 37 therein, may be adjustably mounted on the tubular end frame members 3. The shaft 10 having the roller 11 mounted thereon may be adjustably mounted in the slot 37, so that as the shaft 10 is moved to various positions in the slots 37, 37, the roller 11 will be correspondingly moved and the angle of the portion of the rug strip disposed between the roller 12 and the roller 11 will be changed.

Obviously when displaying the strip of rugs to a prospective customer the handle 33 may be utilized to start, stop and reverse the strip to bring any desired portion of the strip into view, but when the device is installed, for example, in a store window, for general display purposes the actuation of the switch 28 is automatically controlled in the manner above noted.

As a matter of safety a safety switch is provided, as indicated at 40. The switches 26 and 40 and the gear reduction unit 16 are of usual conventional form, procurable on the open market and no claim is made thereto per se.

For the purpose of illustration, if the light should impinge upon the surface of the strip at an angle, such as illustrated at α in Fig. 2, and in so doing did not show the color or design of the rug to the best advantage, due to the lay of the nap of the rugs or other reasons, the roller 11 may be adjusted so as to change its relation with respect to the roller 12, so that the angle of the plane of that portion of the rug strip disposed between the rollers 11 and 12 would be altered to such an extent that the light, being more or less constant, will impinge upon the strip in such a manner that the rug will be displayed to the best advantage.

I claim:

1. In an apparatus for displaying a strip of carpet and the like, the combination of a frame comprising substantially A-shaped end members, a roller disposed in a relatively fixed position on said frame at the vertices of said A frames, a second roller disposed in a predetermined position relative to the first said roller to support a portion of the strip in a predetermined plane therebetween, a bracket carried by and adjustably mounted on the side leg of each A frame, and means for adjustably mounting the second said roller on said bracket affording variations in the plane of the said supported portion of the strip relative to light rays impinging upon said supported portion of the strip to bring out the color and design of the strip to the best advantage for display purposes.

2. In an apparatus for displaying a strip of carpet and the like, the combination of a frame comprising substantially A-shaped end members, a roller disposed in a relatively fixed position on said frame at the vertices of said A frames, a second roller disposed in a predetermined position relative to the first said roller to support a portion of the strip in a predetermined plane therebetween, a bracket mounted for adjustment on and longitudinally of a leg of each of the A frames, each of said brackets having a slot formed therein and extending outwardly from said A frame, a shaft having its opposite ends adjustably mounted in the slots

of said brackets and affording a rotary support for the second said roller.

3. In an apparatus for displaying a strip of carpet and the like, the combination of 5 a vertical frame, a supporting roller for said strip disposed in the upper portion of the frame, guide rolls for the strip carried by the frame in laterally spaced relation to said roller, means for rotating said roller to cause 10 the strip to be passed in a predetermined direction over the said rolls and roller, and means disposed adjacent the base of the frame in substantially vertical alignment with one of said laterally disposed guide rolls and 15 operatively connected to an end of the strip hanging from said vertically aligned guide roll for controlling the actuation of the roller rotating means.

4. In an apparatus for displaying a strip 20 of carpet and the like, the combination of a vertical frame, a supporting roller for said strip disposed in the upper portion of the frame, guide rolls for said strip carried by the frame in laterally spaced relation to said roller, means disposed within the 25 space defined by the strip in passing over said roller and said guide rolls for rotating said roller to cause the strip to be passed in a predetermined direction over the roller and the guide rolls, and means disposed adjacent the base of the frame within said 30 space and operatively connected to the opposite ends of the strip in substantially vertical alignment with said guide rolls respectively for reversing the direction of movement of the roller when a predetermined portion of the strip has passed thereover.

5. In an apparatus for displaying a strip 40 of carpet and the like, the combination of a vertical frame, a supporting roller for the strip disposed at the upper portion of the frame, guide rolls for said strip carried by the frame in laterally spaced relation to said roller, a driving motor disposed within 45 the space defined by the strip in passing over said roller and said guide rolls adapted to rotate said roller, a controlling switch for said motor within said space, means disposed adjacent the base of the frame within 50 said space and operatively connected to the opposite ends of the strip in substantially vertical alignment with said guide rolls respectively for actuating said switch to reverse the motor when a predetermined portion 55 of the strip has passed in a predetermined direction over the roller.

6. In an apparatus for displaying a strip 60 of carpet and the like, the combination of a vertical frame, a supporting roller for the strip disposed at the upper portion of the frame, guide rolls for said strip carried by the frame in laterally spaced relation to said roller, a driving motor disposed within 65 the space defined by the strip in passing over the roller and the laterally spaced guide

rolls and adapted to rotate said roller, a controlling switch for said motor disposed within said space, means disposed adjacent the base of the frame and operatively connected in substantially vertical alignment 70 with said guide rolls respectively to the opposite ends of the strip for actuating said switch to reverse the motor when a predetermined portion of the strip has passed in a predetermined direction over the roller, and means also within said space for manually actuating said switch independent of the last said actuating means therefor.

MARTIN KENNEDY.
